UNITED STATES PATENT OFFICE

BRUCE C. LADD, OF GLENDALE, CALIFORNIA, ASSIGNOR TO THE CLARK GRAVE VAULT COMPANY, OF COLUMBUS, OHIO, A CORPORATION OF OHIO

DISPLAY STAND FOR GRAVE VAULTS

Application filed December 6, 1928. Serial No. 324,143.

This invention relates to an improved support for effecting the display particularly of grave vaults, caskets or other devices employed by undertakers.

5 The primary object of the invention resides in the provision of a supporting stand comprising an integral member of metallic structure and which is formed or bent to include a substantially horizontally extending base portion and an upstanding vertical portion, the base portion being fashioned to receive and support the base of a grave vault and a superposed casket, while the vertically extending portion of the support is shaped or 10 formed to receive the separable hood section of a grave vault, the form of the vertically extending portion of the stand being such as to support the vault hood in a horizontal plane above the base of the vault and the casket resting thereon in order that an observer 15 may readily view and inspect both the base and hood sections of a grave vault as well as the casket.

Another object of the invention resides in 20 forming the stand so that the hood section of the vault will be supported in an acute angular position with respect to the horizontal, the arrangement providing for a compact assembly yet with sufficient separation between 25 the parts being displayed to permit the latter to be completely viewed from substantially any angle.

With these and other objects in view which 30 will appear as the description proceeds, the invention consists in the novel features of construction, combinations of elements and arrangements of parts hereinafter to be fully described and pointed out in the appended claims.

40 In the accompanying drawings:

Figure 1 is a front elevation of the display stands comprising the present invention, illustrating the use thereof effecting display of undertakers' appliances.

45 Figure 2 is a view in end elevation of one of the display stands, showing more particularly the construction of the stand whereby the base and hood sections of a grave vault are maintained in spaced relationship,

50 Figure 3 is a perspective view of the dis-

play stand comprising the present invention.

Referring more particularly to the drawings, the numeral 1 designates the display stand comprising the present invention. In practice, a pair of these display stands are 55 utilized to effect the support of the base section 2 of a metallic grave vault, the hood section 3 of said vault and, if desired, a casket 4, which rests upon the upper surface of the vault base section 2.

To effect this result each of the display stands 1 is formed preferably from metallic rod material, which is bent, wrought or otherwise fashioned to produce a horizontally extending base portion 5. The outer end of 60 this portion is bent downwardly and vertically to produce a forward leg 6, while the inner end of the base portion 5 terminates in a pair of downwardly extending outwardly diverging legs 7, which impart stability to the 65 stand and enables the latter readily to sustain its upright position under the loads imposed thereon.

The inner end of the base portion 5 terminates in an upwardly extending vertically disposed hood supporting section 8, and the extreme upper end of this section 8 terminates in an angularly bent portion 9, which lies at an acute angle with respect to the plane of the upright portion 8. Adjacent to the point of 70 juncture of the vertically and angularly extending portions 8 and 9 of the stand there is provided an integral supporting hook 10, which extends rearwardly from the portion 75 8. It will be observed that the construction 80 of the display stand is such that the parts thereof lie in the same vertical plane with the exception of the diverging legs 7. This is the feature which enables the display stand when not in use, or when being transported, 85 to be compactly stored so as to occupy but a minimum of space.

Each of the display stand units is self supporting, that is, the construction of the legs 90 6 and 7 enable each unit to stand without extraneous assistance. In practice the stands are spaced apart a desired distance and rest upon the floor surface. Then, there is placed 95 upon the base portions 5 of said stands the base section 2 of a metallic grave vault, and 100

upon this base section there may be superposed a casket 4. To support the hood section 3 of the vault the lower longitudinal edges of said hood section, as shown in Figure 2, are engaged with the hook portions 10 of the stand units. It will be observed that the flare 11 provided at the lower edge of the hood section readily enters the open sides of the hooks 10 and further, the obliquely extending portions 9 of the stand enter the interior of the hood section and engage with the inner walls thereof. It will be seen that by this construction the hood is supported in an angular position with respect to the horizontal from one side thereof. The tendency of the hood is to swing or rotate in a forward direction. This movement or tendency thereof, however, is arrested by the engagement between the lower portion of one side of the hood and the vertical legs of the hooks 10, and also by the engagement between the inner surface of one of the side walls of the hood and the angularly extending portions 9 of the supporting stand. The arrangement permits the vault and casket parts to be readily assembled in display positions and provides for effective observation or inspection of the vault and casket units. If desired, portable and removable electric light 30 may be inserted in the hood section of the vault to more thoroughly display the articles supported by the stand.

In view of the foregoing it will be seen that the present invention provides a display stand of simple, efficient and economic construction well adapted to the specific uses above set forth. It should be understood that I do not limit myself to the precise details of construction herein described but reserve the right to employ all such modifications thereof that may be said to fall within the scope of the following claims. For example, the display units 1 may be united by longitudinally extending members, if desired. 45 However, I prefer to form these display units separately for convenience in handling, storage and transportation, although it is within the scope of the invention to positively unite the same if desired.

50 What is claimed is:

1. A display stand for grave vaults comprising an integral metallic structure formed to include a horizontally extending base portion having downwardly extending legs at the opposite ends thereof, an upright portion formed with one end of said base portion, said upright portion terminating in an angularly bent portion lying at an acute angle with respect to the vertical, a hook formed with said upright portion and extending rearwardly therefrom in a plane below the angularly bent portion, the base portion of said stand, the upright portion, the angularly bent portion and the hook device being arranged in the same vertical plane,

2. A display stand for grave vaults, comprising a base frame formed to effect the support of the base section of a metallic grave vault in a substantially horizontal position, an upright portion formed with one end of said base section, said upright portion terminating in an angularly disposed portion lying at an acute angle with respect to the vertical, a hook formed with said upright portion and extending rearwardly therefrom in a plane below the angularly bent portion and above said base section, the base section of said stand, the upright portion, the angularly bent portion and the hook device being arranged in the same vertical plane.

3. A display stand for grave vaults comprising a horizontally extending base portion, supporting legs depending from said base position, a vertically extending portion rigidly associated with one end of said base portion, said vertically extending portion terminating at its upper end in an angularly disposed rearwardly inclined portion bent at an acute angle with respect to the vertical, and a hook device rigidly formed with said vertically extending portion and projecting rearwardly therefrom, said hook device being situated adjacent the juncture of said vertically and angularly extending portions and arranged above the plane of said base portion and in the same vertical plane as said angularly extending portion.

In testimony whereof I affix my signature.
BRUCE C. LADD.
